UNITED STATES PATENT OFFICE.

ALONZO ALDRICH, OF BELOIT, WISCONSIN.

PAPER-MAKING MACHINE.

1,421,754.

Specification of Letters Patent. Patented July 4, 1922.

Application filed July 16, 1921. Serial No. 485,180.

To all whom it may concern:

Be it known that I, ALONZO ALDRICH, a citizen of the United States, residing at Beloit, in the county of Rock and State of Wisconsin, have invented a certain new and useful Improvement in Paper-Making Machines, of which the following is a full, clear, concise, and exact description, reference being had to the accompanying drawings, forming 10 a part of this specification.

My invention relates to paper making machines, and particularly to machines known in the trade as Fourdrinier machines.

One of the objects of the invention is to 15 provide a practical and advantageous construction of Fourdrinier machine.

Another object of the invention is to arrange for the quick and ready placing of a new wire in the machine, after the old wire 20 has been ripped or torn off.

Another object of the invention is to simplify the construction so that the operation of placing a new wire in the machine will involve a minimum amount of changing 25 of the parts and labor.

In the accompanying drawings Fig. 1 is a side elevation of a portion of a Fourdrinier machine embodying my present invention and in operating condition with a wire in 30 place;

Fig. 2 is a similar view of said machine in the process of inserting a new wire;

Fig. 3 is an end elevation of the machine at the beginning of the process of changing 35 a wire;

Fig. 4 is a view similar to Fig. 3 with the new wire being put in place; and

Figs. 5 and 6 are views similar to Figs. 3 and 4, respectively, of a modified form of 40 machine.

Referring to the drawings, and particularly to Figs. 1 to 4, inclusive, I show a machine having a table 1 provided with rolls 2—2 supporting a wire 3. The feed end of 45 the table is supported by cables 4 having couplings 5 engaging brackets 6. The cables 4 extend up over winding drums 7 which are actuated by rotary shaft 8 driven by gears 9 and 10 from electric motor 11. A clutch 12 controlled by a lever 13 permits the control of the motor 11 so as to operate 50 the winding drums 7 and thereby raise or

lower the feed end of the table 1 as desired.

The other end 1^a of the table is supported on a rocker 15 by which a slight extent of movement of the table is permitted as required by the raising and lowering of the feed end. The table may be shaken if desired by connecting suitable shaking mechanism, as for example, a bell-crank and operating means connected to one side of the table near the feed end. As such mechanism is well known in the art, it is not shown here.

The head box 16 is also arranged to be 65 raised and lowered and is shown connected by a clamp 17 with the side pieces 18 on the table 1. Cables 19 and 20 are shown connected with the head box 16 and these cables are shown extending up over winding drums 70 21 and 22 respectively. The frame 21 is operated by a belt 23 running to the drum 22 and the latter is operated by means of shaft 8 and clutch 24 thereon controlled by a lever 25, whereby operation of lever 25 75 may throw clutch 24 into engagement with shaft 8 and thereby cause motor 7 to elevate head box 16. For adjusting the pitch of the table 1, the feed end thereof and the head box 16 are raised and lowered as desired by 80 operating levers 13 and 25.

The deckel straps 27 are shown running over deckel wheels 28 and 29 at or near the opposite ends of the table.

In order to permit the placing of a new 85 wire on the machine, the table 1 is arranged to be run out bodily in a lateral direction so that it may be placed in front of the position it usually occupies so as to permit the new wire to be stretched and placed in 90 the usual position around the space normally occupied by the table, after which the table may be moved back into its normal position, passing between the upper and lower plies or reaches of the wire so that operation may 95 be resumed with the wire in its proper place above and below the table.

In accordance with the present invention, provision is made for lifting and moving forward the front edge of the table and for 100 supporting and permitting the forward movement of the rear edge of the table. To such end I show overhead traveling, lifting and pulling units 30 and 31, conveniently

in the form of overhead trolley devices having trolley wheels 32—32 running on overhead tracks 33, said units 31 also having winding drums 34 adapted to wind cables 35, the units 30 and 31 being provided with mechanism, preferably in the form of electric motor devices for rotating the wheels 32 to cause movement along the track 33 and being also provided with mechanism, preferably 10 electric motor devices, for rotating wheels 34 to cause winding and unwinding of the cables 35. Thus the cables 35—35 may be engaged with the front edge of the table 1 as by passing them over noses 37 15 on the table, and by operating the winding drums 34 the front edge of the table may be elevated slightly, as shown in Fig. 3. Then by rotating the wheels 32 the units 30 and 31 may be moved so as to pull the front 20 edge of the table forwardly, as shown in Fig. 4.

To permit the proper travel of the rear edge of the table during its forward movement, said rear edge is provided with 25 wheels 38, and tracks 39 are mounted on pedestals 40 and 41, whereby the wheels 38 will travel along the rails 39 as the table moves forwardly. These rails 39 are understood not to be in position in the machine 30 normally, but are to be inserted (as shown in Fig. 3) when it is intended to move the table to permit insertion of a new wire.

In order to put a new wire in place in the machine, the old wire is removed as by 35 ripping or tearing it off from the table. The cables 35 are connected with the front edge of the machine, the lifting and pulling units 30 and 31 being located above said front edge, as seen in Fig. 3. The table is then 40 disconnected from the head box 16 by removing clamp 17 and the cable 4 unhooked. The lifting and pulling units 31 are then operated so as to elevate the front edge or side of the table a slight extent, as shown 45 in Fig. 3, and are then further operated so as to pull the table outwardly or forwardly to a fully removed position, as seen in Fig. 4. The deckel strap 27 and wheels 28 have been previously elevated, as shown in Fig. 50 2, so as to permit this movement of the table.

The couch roll 43 is lifted from its bearing and the new wire slipped over it and the couch roll then elevated. The new wire 55 is then extended along the machine between the supports or foundations of the table. Pipes such as 44, 45, 46 and 47 (Fig. 2) are inserted below the upper ply or reach of the new wire so as to support the same 60 in a lifted position. Other pipe such as 48, 49, 50, 52 and 53 are placed over the lower stretch of the new wire so as to hold the same down. These latter pipes are so placed as to make space for the various projecting parts of the table, such as the

brackets 6 and 1^a, and the tension device 55. The table is then moved back to its normal position by operating the units 30 and 31, the wheels 38 traveling on the rails 39 and the front edge of the table being supported 70 and moved by the movement of the units 30 and 31 when the table is moved back. Its front edge is lowered and its feed end is engaged and lifted by the cables 4, the rails 39 are removed, the couch 43 and other 75 parts are put back in position and the machine is ready for operation with its new wire.

It will be seen that this operation can be quickly and readily performed; and that 80 only one set of rails 39 is necessary, the front edge of the table being supported and moved by other mechanism.

Referring to the modification shown in Figs. 5 and 6, I show an arrangement by 85 which the table 1 can be moved laterally by power means located at one side of the table, but not above the same. In this modification I show tracks or rails 60 at one side of the normal position of the table 1, the same being 90 preferably supported by posts 41^a and 61. An endless chain 62 is arranged in connection with one set of tracks 60, traveling over sprocket wheels 63 and 64 at the opposite ends of said tracks. A power generator 65, 95 which may be an electric motor, is shown mounted on the post 61 and connected by pinion 66 and gear 67 with the sprocket 64, so that said chain 62 may be operated by the motor 65.

The table 1 is provided with a hook member 69 which is adapted to engage the upper stretch of the chain 62. Thus by engaging the hooked member 69 with the chain 62, the table 1 may be run out to one side of its normal position, as shown in Fig. 6. When this is done the tracks 39 may be removed so as to permit the new wire to be extended along between the posts 40 and 41^a, as previously explained in connection with the form of 105 machine illustrated in Figs. 1 to 4, inclusive. When the wire is thus properly arranged, the table 1 may be returned to its normal position by reversing the motor 65 and causing the chain 62 to move in a reversed manner and thereby push the table back to its 110 normal position.

In order that the rails 60 may be moved and kept normally out of the way, said rails are preferably pivoted to the posts 61 so 120 that they may be swung upwardly as shown in dotted lines in Fig. 5.

Reference is made to application Serial No. 469,552 filed May 14, 1921 in the name of myself and A. L. Lawson for paper making machines, said application disclosing and claiming certain of the broad features of construction and operation set forth in this application.

It will be understood that changes and 130

modifications may be made without departing from the spirit of the invention.

What I claim as new is:

1. In a machine of the class specified, the 5 combination of a laterally movable table, and overhead means for lifting the front edge of the table and moving the table laterally.

2. In a machine of the class specified, the 10 combination of a laterally movable table, and overhead means for drawing the table out to one side.

3. In a machine of the class specified, the 15 combination of a laterally movable table, overhead means for engaging and drawing upon the front edge of the table, and means for supporting and permitting the forward and backward travel of the rear edge of the table.

4. The combination with a laterally movable 20 table, of power means separated from the table and flexible connectors between the power means and the table for moving the table out to one side.

5. The combination of a laterally movable 25 table, rails below the table, wheels on the rear of the table arranged to travel on said rails, means for lifting the front edge of the table, and means for moving the table with its front edge elevated and its rear edge 30 traveling on said rails.

6. The combination of a laterally movable 35 table, rails below said table, wheels on the rear edge of the table for traveling on said rails, and pulling means connected to and supporting the front edge of the table for moving the table laterally.

7. The combination of a laterally movable 40 table, rails below said table, wheels on the rear edge of the table for traveling on said rails, and lifting and pulling means for elevating and lowering the front edge of the table and moving the table laterally.

8. The combination of a laterally movable 45 table, rails below said table, wheels on the rear edge of the table for traveling on said rails, and lifting and pulling means for elevating and lowering the front edge of the table and moving the table laterally, said lifting and pulling means comprising overhead lifting 50 and pulling units arranged to travel on overhead rails, and provided with lifting and propelling mechanism.

9. The combination of a laterally movable 55 table, means for permitting the lateral movement of the table and power means in front of the table connected with the same for supporting and moving the table.

10. The combination of a laterally movable 60 table, means for permitting the lateral movement of the table, flexible means connected with the table and extended in front of the same and a power generator in front of the table connected with said flexible means for moving and supporting the table.

65 11. The combination with a table mounted

for sidewise shaking movement and also mounted to permit bodily elevation, of means for elevating the front edge of the table and means permitting the sidewise or lateral movement of the table.

70

12. The combination of a table mounted for sidewise shaking movement and also mounted for bodily elevation, means for raising and lowering the feed end of the table, tracks extending sidewise of the table 75 on which the same may be moved laterally and means for lifting one side or edge of the table and moving the same laterally.

13. The combination of a table mounted for sidewise shaking movement and also 80 mounted for bodily elevation, means for raising and lowering the feed end of the table, laterally extending tracks extending sidewise on which the table may be moved laterally and means for lifting one side or 85 edge of the table and moving the same laterally, said last mentioned means comprising overhead lifting and pulling units connected with said edge or side of the table and overhead tracks on which said pulling 90 units operate.

14. The combination of a table mounted for sidewise shaking movement and also mounted for bodily elevation, means for raising and lowering the feed end of the 95 table, laterally extending tracks extending sidewise on which the table may be moved laterally and means for lifting one side or edge of the table and moving the same laterally, said last mentioned means comprising 100 overhead lifting and pulling units connected with said edge or side of the table and overhead tracks on which said pulling units operate, a vertically adjusted head box and means for raising and lowering said 105 head box.

15. The combination of a table mounted for sidewise shaking movement and also mounted for bodily elevation, means for raising and lowering the feed end of the table, 110 laterally extending tracks extending sidewise on which the table may be moved laterally and means for lifting one side or edge of the table and moving the same laterally, said last mentioned means comprising 115 overhead lifting and pulling units connected with said edge or side of the table and overhead tracks on which said pulling units operate, a vertically adjusted head box and means for raising and lowering said head box, said means for raising and lowering the table feed end and the head box comprising an electric motor, winding drums and clutch arrangements for connecting said motor with said winding drums.

125

16. The combination with the laterally movable table of laterally extending tracks on which the table may be moved, a flexible connector on said side tracks, means for connecting and disconnecting the table with 130

said flexible connector and a power generator also on said side tracks for moving said flexible connector.

17. The combination with the laterally movable table of laterally extending tracks on which the table may be moved, a flexible connector on said side tracks, means for connecting and disconnecting the table with

said flexible connector, a power generator also on said side tracks for moving said flexible connector, and means for swinging said laterally extending tracks upwardly about their outer ends as pivots.

In witness whereof, I hereunto subscribe my name this 16 day of June A. D., 1921. 15

ALONZO ALDRICH.
